Inventor:

Adam Herig,
by Geo. W. Tibbitts, Attorney.

UNITED STATES PATENT OFFICE.

ADAM HERIG, OF CLEVELAND, OHIO.

HEAT-DISTRIBUTER.

SPECIFICATION forming part of Letters Patent No. 720,346, dated February 10, 1903.

Application filed May 20, 1902. Serial No. 108,286. (No model.)

To all whom it may concern:

Be it known that I, ADAM HERIG, a citizen of the United States of America, and a resident of Cleveland, county of Cuyahoga, and 5 State of Ohio, have invented certain new and useful Improvements in Heat-Distributers, of which the following is a specification.

This invention relates to heat-distributers for hot-air furnaces; and it consists of additional improvements on my Patent No. 687,154, dated November 19, 1901. These improvements have for their object to provide for making the distributor adjustable, so as to make it capable of adjustment to fit different-sized register-boxes, thus avoiding the necessity of making several sizes of distributors for the little variations in the sizes of registers.

This improvement consists in making separate corner-pieces and side and end plates for the distributor-boxes and joining said parts together with bolts inserted through slots to enable them to be easily and exactly increased or diminished in length and width 25 to adapt them to the register-box.

In the accompanying drawings, Figure 1 is a perspective view of my improved distributor-box. Fig. 2 is a vertical section on line 2 2 on Fig. 1. Fig. 3 is a detached view of 30 one of the corner-pieces. Fig. 4 is a similar view of a corner-piece with extended sides.

D D are corner-pieces that may be made of one piece of metal cut and bent to form the outside and inside walls d d' . The inside 35 walls, which form the hot-air flue, and which is somewhat smaller than the outside casing, have a portion cut away at the middle and have the cut edges brought together and joined to make the inside corner-seam d'' of the 40 said inside air-flue and the downward corner extensions d^3 . These extensions are provided to be inserted in the inside edges of the register-boxes for retaining them in place. This construction provides the open space between

the outside walls of the box and the walls of 45 the hot-air flue.

E E are perforations in the lower parts of the outer walls for the admission of the cold air from the floor, and the chamber within the inside walls forms the flue for the passage of hot air from the furnace.

F G represent, respectively, the side and end plates of the distributor-box, which are formed with two walls in like manner to the corner-pieces. They are provided with slots 55 e e , and when their side edges are inserted in the corner-pieces are secured in place by bolts g g through the corner-pieces and the said slots, the obvious purpose and object of which is that the said corner-pieces and the 60 side and end plates may be adjusted for increasing or diminishing the width and length of the box for closely fitting the floor register-boxes B, which frequently differ in size.

Fig. 4 represents a corner-piece of greater 65 width than D D, which may be joined together with a lap at the middle of the sides and ends of the box and fastened by bolts in slots in like manner to the corner-pieces D to the side plates F G. This method may be employed in making small-sized boxes.

Having now described my invention, what I claim is—

The heat-distributer consisting of the corner-pieces D D, comprising an inner and an 75 outer wall and provided with the projections d^3 , the side and end plates composed of an inner and outer wall, the outer wall being provided with perforation E for the admission of air, and slots e adapted to engage with 80 bolts inserted in the corner-pieces D, substantially as described.

Signed by me at Cleveland, Ohio, this 16th day of May, 1902.

ADAM HERIG.
